UNITED STATES PATENT OFFICE.

LAWRENCE M. CAMPAN, OF OCONTO, NEBRASKA.

PUMP FOR SPRAYING DEVICES.

1,071,876.

Specification of Letters Patent.

Patented Sept. 2, 1913.

Application filed April 8, 1911. Serial No. 619,640.

To all whom it may concern:

Be it known that I, LAWRENCE M. CAMPAN, a citizen of the United States, residing at Oconto, in the county of Custer, State of Nebraska, have invented certain new and useful improvements in Pumps for Spraying Devices; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to a device for supplying air pressure to portable spraying tanks, and consists in the construction and arrangement of parts hereinafter more fully set forth and pointed out particularly in the claim.

The object of the invention is to provide simple and efficient means actuatable by the operator in walking, or adapted to be actuated by a movement of the feet of the operator, whereby a constant supply of air under pressure may be furnished to a spraying tank used in the spraying of trees and shrubbery. The above object is attained by the apparatus illustrated in the accompanying drawings, in which:

Figure 1 is a perspective view illustrating the application of my invention. Fig. 2 is a perspective view of one of the foot pieces to which is attached an air compressor. Fig. 3 is an enlarged perspective view of one form of an air compressor adapted for this purpose, detached from the foot piece. Fig. 4 is a longitudinal section through the foot piece and air compressor, the air pipes and attaching straps being broken away, the section through the bellows or air compressor being taken as on line 4-4 of Fig. 3. Fig. 5 is a horizontal section through the bellows or air compressor, as on line 5-5 of Fig. 4.

Referring to the characters of reference, 1 designates a spraying tank adapted to contain the fluid to be sprayed, and into which air is forced to create the necessary pressure, through the intake pipe 2. Communicating with the air intake pipe 2 are the air supply pipes 3. At the juncture of said pipes is placed a suitable relief valve 4.

Leading from the underside of the tank is a spray pipe 5 having the usual nozzle 6. All

of this apparatus is carried on the operator, as shown in Fig. 1.

To provide for compressing the necessary quantity of air and forcing it into the tank 1, foot pieces 7 are employed adapted to be fastened to the feet of the operator by the attaching straps 8 and 9. The foot piece is provided with a suitable heel 10 and on the under side of the sole thereof is secured an air compressor which I have herein illustrated in the form of a bellows, consisting of a top plate 11 through the medium of which it is secured to the foot piece, and a bottom plate 12 which is hinged to the top plate at its front end. Connecting the two plates 11 and 12 is the usual flexible material 13 rendered impermeable to air.

Interposed between the two plates of the bellows is a compressible spring 14 which serves to hold the bottom plate distended. 75 Communicating with each bellows or air compressing device is an intake pipe 14^a having a suitable check valve 15 therein through which a volume of air may be drawn as the bellows expands. The air supply pipes 3 communicate with the air compressors, respectively, and are provided with suitable check valves 16, as shown in Fig. 3. The terminals of the intake pipes 14^a are so supported as to prevent the entrance of dust 80 and dirt thereinto. With the air compressors secured to the feet of the operator, the operation of walking will successively actuate said compressors to force a quantity of air from each under pressure into the tank 90 2, as the weight of the operator is borne first upon one foot and then upon the other. In each instance as the weight of the operator is lifted from the compressor, the spring 14 will operate to expand the bellows to draw 95 thereinto a quantity of air for a succeeding operation. In like manner the air may be compressed when the operator is standing by alternately shifting his weight from one foot to the other.

It will now be apparent that by the use of this device, an unlimited quantity of air may be supplied to the pressure tank in a simple and efficient manner, obviating the necessity of pumping the air into the tank 105 by hand to create the necessary pressure. It will further be observed that with this device, the supply of air is practically continuous, thereby enabling a uniform pressure in the tank to be maintained.

Having thus fully set forth my invention, what I claim as new and desire to secure by Letters Patent, is:—

1. A pump for spraying devices comprising foot pieces adapted to be secured to the respective feet of the operator, air compressors in the form of bellows attached to the respective soles of said foot pieces, valve controlled air intake pipes communicating respectively with said compressors and having their free ends supported above said foot pieces, and an air educt pipe adapted to be connected to a pressure tank and having a valve controlled branch leading from each of said air compressors whereby a constant pressure is created in the pressure tank.
2. A pump for spraying devices comprising foot pieces adapted to be secured to the respective feet of the operator, bellows at-

tached to the respective soles of said foot pieces, the movable side of the said bellows hinged to the toe of the said foot pieces, heels extending substantially to the lower edge of the movable side of the said bellows, valve controlled air intake pipes communicating respectively with said bellows and having their free ends supported above said foot pieces, and an air educt pipe adapted to be connected to a pressure tank and having a valve controlled branch leading from each of said air bellows.

In testimony whereof, I sign this specification in the presence of two witnesses.

LAWRENCE M. CAMPAU.
